UNITED STATES PATENT OFFICE.

FRANK J. GRIDLEY, OF NEW YORK, ASSIGNOR TO THE UNDERWRITERS
HATCH DOOR COMPANY, OF BROOKLYN, NEW YORK.

SELF-CLOSING HATCHWAY.

SPECIFICATION forming part of Letters Patent No. 404,618, dated June 4, 1889.

Application filed December 10, 1888. Serial No. 293,100. (No model.)

To all whom it may concern:

Be it known that I, FRANK J. GRIDLEY, of Brooklyn, in the county of Kings and State of New York, have invented new and Improved

5 Self-Closing Hatchways, of which the following is a full, clear, and exact description.

My invention relates to an improvement in safety devices for elevator-shafts, light-shafts, and other openings, and has for its object to 10 provide a means whereby should a fire happen in the building in which the shaft is located the devices retaining the shaft-doors will be released by the heat and permitted to automatically close; and the further object of 15 the invention is to provide a device capable of accomplishing this result, which will be of simple and effective construction.

The invention consists in the novel construction and combination of the several parts, 20 as will be hereinafter fully set forth, and pointed out in the claims.

Reference is to be had to the accompanying drawings, forming a part of this specification, in which similar letters of reference indicate 25 corresponding parts in all the figures.

Figure 1 is a central vertical section through an elevator-shaft fitted with my improvement. Fig. 2 is a transverse section on line $x-x$ of Fig. 1. Figs. 3 and 4 are perspective views of 30 the catches employed at right and left of the shaft, and Fig. 5 is a detail view of the fusible connection of tripping device.

In carrying out the invention, A represents an elevator-shaft, and B the several floors 35 through which the shaft passes. Between the floors, at each side of the shaft, latch-bars C C' are respectively pivoted, the latches C to the left having their heads C² facing downward, the latch-heads to the right being made to 40 face upward, as best shown in Figs. 1, 3, and 4.

The latches are each provided with a spring C³, attached to the wall bearing upon one side, and a stop C⁴ is also provided, adapted to limit the upward movement of the latches 45 upon the right and the downward movement of those upon the left. At each floor doors D are hinged adapted when brought to a horizontal position to abut and constitute a platform bridging the shaft and fitting snugly to 50 the walls thereof. Each door is provided

with a latch-pin D', rigidly secured to the upper surface, purposed to interlock with the respective pivoted latches C and C', as best shown in Fig. 1.

Within the shaft at the bottom a block E 55 is located, upon which block an elbow-lever d is pivoted, having attached to the vertical member a horizontal trip-arm d', capable of sliding in a guide fixed to the block. The free end of the trip-arm d' is made to normally support a hinged door E', covering a pit E², located at one side of the shaft, as best shown in Fig. 1.

A weight E³ normally rests upon the hinged door E', having secured thereto a 65 weight-actuated rope or chain E⁴, which rope or chain is passed upward through the floors at one side of the shaft over pulleys d² and d³, situated at the top of said shaft, and down upon the other side, the end of the rope or 70 chain opposite to that carrying the weight being connected with the floor by a spring d⁴, which spring is adapted to take up the slack. The weight-actuated rope or chain E⁴ is attached to each of the pivoted latches C and 75 C' by means of a loop e, or in any other approved manner.

A second trip rope or chain F is attached to one wall of the shaft, and the said rope or chain extending downward is made to pass 80 over spaced and vertically-aligning pulleys e' e², pivoted at each floor, and a weight F' is attached to the lower end of the rope or chain, the normal position of which is immediately above the horizontal member of the 85 elbow-lever d. A release-rod H is held to slide upon the ceiling of the several floors, provided at one end, which extends within the shaft, with a pulley h, the trip rope or chain F being passed over the several pulleys 90 h before passing over the lower pulley e² of the pair located at each floor, as best shown in Figs. 1 and 5. The releasing-rod extends only a short distance within the shaft, whereby the rope F at each floor is more or less horizontally looped in direction of one side of the shaft. The end of the releasing-rod opposite to that carrying the pulley h is attached to a retaining rope or chain K by a 95 fusible link K', the said rope or chain K being 100

secured at the other extremity to the ceiling in any approved manner.

In operation, when the doors are fastened up in position, should a fire occur in the 5 building, the heat fuses the link K, whereupon the rod H releases its hold upon the rope F and the weight F' falls upon the elbow-lever, causing the latter to slide the arm d' inward and withdraw its support from the trap-door 10 E'. When the door drops down, the weight F' falls into the pit E², which action of the weight releases the several latches C and C' from engagement with the doors D, permitting the latter to drop to their closed position, 15 effectually cutting off a draft up the shaft.

Having thus described my invention, what I claim as new, and desire to secure by Letters Patent, is—

1. The combination, with a series of doors 20 and pivoted latches capable of engaging with said doors, of a drop or trap door, a lever engaging with said door, a weighted trip-rope suspended over said lever, a rope connected to the latches and having a weight supported 25 on the drop or trap door, a retaining-rope, and a fusible connection between said retaining and trip ropes, substantially as shown and described.

2. The combination, with a series of doors, 30 latches to engage said doors and hold them open facing, respectively, in opposite directions, a spring-actuated weighted rope connected with said latches, and a drop or trap door supporting said weight, of a lever engaging with the trap-door, a weighted trip-rope suspended over said lever, a retaining-rope, and a fusible connection between said trip and retaining ropes, substantially as shown and described. 35

3. The combination, with a series of doors 40 provided with fixed latch-pins, pivoted latches engaging with the fixed latch-bars, a spring-actuated weighted rope connected with said latches, and a drop or trap door supporting the weight of said rope, of a weighted trip-rope, a lever pivoted beneath said trip-rope, a sliding trip-arm attached to the lever and engaging the trap-door, a release-bar connected with the trip-rope, a retaining-rope, and a fusible connection between said releasing-bar and 45 retaining-rope, substantially as shown and described.

4. The combination, with a series of doors provided with fixed latch-pins, pivoted latches to engage said doors, a spring-actuated rope 55 attached to said latches carrying a weight, and a trap or drop door supporting said weight, of pulleys arranged in pairs, a weighted trip-rope passing over said pulleys and provided with horizontal open loops, a release-bar having a 60 pulley attached engaging with the said loops, a retaining-rope united to said release-bar by a fusible connection, an angled lever below the trip-rope, and a sliding trip-arm attached to said lever and supporting the trap-door, 65 substantially as shown and described.

5. The combination, with the hinged doors and latches engaging with said doors, having a weighted operating-rope, of a retaining-rope, a trip-rope, a release-bar connected therewith, 70 and a fusible link uniting the retaining-rope and release-bar, all arranged to operate substantially as shown and described.

FRANK J. GRIDLEY.
